DESIGN FOR A CONSTANT CURRENT REGULATOR

Hugh E. Young and Eugene H. Haug, Chicago, Ill.

Application September 2, 1938, Serial No. 79,691

Term of patent 14 years

To all whom it may concern:

Be it known that we, Hugh E. Young and Eugene H. Haug, citizens of the United States, residing at Chicago, in the county of Cook and State of Illinois, have invented a new, original, and ornamental Design for a Constant Current Regulator, of which the following is a specification, reference being had to the accompanying drawing, forming a part thereof.

The single figure in the drawing is a perspective view of a constant current regulator as it would appear from either side, and showing our new design.

We claim:

The ornamental design for a constant current regulator, substantially as shown and described.

HUGH E. YOUNG.
EUGENE H. HAUG.
